CLAIM

The ornamental design for a support and charging base for a shaver, as shown and described.

DESCRIPTION

FIG. 1 is a perspective view of a support and charging base for a shaver showing our new design;
FIG. 2 is a rear elevational view thereof;
FIG. 3 is a top plan view thereof;
FIG. 4 is a bottom plan view thereof;
FIG. 5 is a left side elevational view thereof; the right side being a mirror image; and
FIG. 6 is a front elevational view thereof.
